UNITED STATES PATENT OFFICE

RUDOLPH KRAUS, OF WHITESTONE, NEW YORK

GAS DETECTOR

Application filed August 27, 1929. Serial No. 388,795.

This invention relates to improvements in gas detectors and alarm signal sounding devices, for automatically detecting the presence of gas in a living or working room, and then sounding an audible signal, which will be automatically repeated for a prolonged period of time, until a person responds to the signal and rests the mechanism, after stopping the gas leakage.

One of the objects of the invention is the provision of a device which will have a positive action in detecting the presence of gas, as gas leaking from a stove jet or other device, by drawing or guiding the gaseous constituents of a part and preferably of several parts of a room, and by the aid of the same causing a small flame to be produced by the gas, so as to release a signalling mechanism, preferably one normally restrained from operation by a combustible cord located over the path of the flame generated by the escaping gas, or by an equivalent, as a fusible element or other element or means deformable, destroyable or actuatable by an abnormal thermal condition in its vicinity.

Other objects and advantages of the invention will be hereinafter specifically pointed out, or will become apparent as the specification proceeds.

With the above indicated objects in view, the invention resides in certain novel construction and combination and arrangement of parts, clearly described in the following specification and fully illustrated in the accompanying drawings, which latter show an embodiment of the invention as at present preferred.

In the drawings:

Figure 1 is a side elevation of the complete mechanism, with the side plate of the casing removed.

Figure 2 is a detail horizontal sectional view taken on line 2—2 of Figure 1 looking in the direction of the arrows.

Figure 3 is a detail view in section of the spark producing drum and flame generator, taken on line 3—3 of Figure 1, looking in the direction of the arrows.

Figure 4 is a view in perspective of the casing.

Similar reference characters refer to similar parts throughout the several views of the drawings.

Referring to the accompanying drawings in detail, 5 designates a casing, the cover wall 6 of which may be removed. In this casing a gear train is mounted, and this consists of the four main gears 7, 8, 9 and 10. The gear 7 is supported by its staff 7^a for rotation on the bearing support or frame 11, 60 carried by the casing 5, and the usual main spring 7^c is mounted against the side of the gear, to be wound by the key 7^d. The gear 7 meshes with the gear 8 which is supported upon the shaft 8^b, also rotating in bearings 65 of the frame 11. This gear 8 is provided with a pinion gear 8^a, which is in mesh with the gear 9, supported for rotation by its staff 9^a upon the frame 11. This gear 9 carries a pinion gear 9^a, which meshes with the gear 10. In general construction this gear train follows well known practice.

The gear 8 is provided with a laterally striking pin 8', which is designed to repeatedly engage and tilt the lever 12, which is pivoted at 12^a to rock against the tension of the pull spring 12^b. This lever is provided on its forward and upper end with an angular arm 13 on which the spring 14 is mounted. This spring carries on its upstanding end a 80 U-shaped clamp 15, between the jaws of which the upper end of the curved igniter arm 16 is clamped by the screw 17.

The igniter arm carries on its pendant lower end the usual tip of ceric iron, to engage 85 the conical abrasive drum 18, which is mounted to rotate upon the bearing 19, supported from the casing 5 by the horizontal arm 20. A ratchet wheel 21 is mounted on the outside of this drum, to be engaged and intermittently moved by the pawl 22, which is pivoted at 23 to the lever 12.

To the gear 10 a pitman 24 is provided at one end and at the other is pivoted to the connecting clip or bracket 25, mounted on the movable wall or member 26 of a bellows 27, the fixed wall or member 28 of which is supported by the air intake pipe 29, the forward end of which pierces the casing 5 and is suitably clamped thereto.

From this bellows the conduit 30 rises and communicates with the bulbous member 31, the open upper end of which extends into the abrasive drum 18. Each time the gear 10 makes a revolution the pitman closes and then opens the bellows, so that air from the outside is sucked through the intake pipe 29 and forced into the conical drum 18.

Each time the gear 8 makes one revolution the striking pin 8' thereof will rock the lever 12, so that a spark will be produced by the action of the ceric iron tip against the abrasive surface of the rotating drum 18. This spark producing rocking action occurs more frequently than the closing and opening of the bellows, due to the higher speed of the gear 8.

When gas is present in the room, exterior to the casing, some of it will be sucked into the bellows and forced into the conical drum 18, and being mixed with air will readily ignite, thus generating a flame over this drum 18.

A combustible cord or element 32 is supported at one end to the hook or fastener 33 carried by the casing 5 and at the other end is connected to the spring bar 34, the lower end of which is fixed to the casing at 34^a. To this spring bar a link 35 is pivoted at its upper end, its lower end having a hook to engage the pitman 24. The combustible cord 32 is supported immediately above the cone 18 and when the flame is generated the cord will be consumed or weakened to allow the tension of the spring bar or arm 34 to break it, thus lifting the link 35 and causing its hook 36 to pull against the pitman 24, the forward end of which has a lateral slot 24' to permit it being disengaged from its forward pivotal connection with the bellows. This will render the bellows inoperative. The spring bar 34 also carries a pendant link 34^a.

At the same time the pendant link 37, carried by the spring bar 34, and equipped with a terminal hook 381, will engage the sparking lever 12, tilting it upon its pivot, so that its lower end will be shifted out of the circular path of the striking pin of the gear, 8, thus preventing any further production of sparks.

When this action takes place the terminal portion 39^a of the spring 39, which is fixed at one end to the casing 5, will force the upper end of the signal lever 40, which is normally elevated above the bell 41, into engagement with said bell and bring the rear end of said lever into the circular path of the series of pins 9' on the side of the gear 9; the link 34^a which normally restrains the lever 40 being elevated out of the way. This will result in the signal lever being repeatedly rocked upon its pivot, against the pressure exerted by the weighted striking terminal or clapper 40^a of said signal lever, thus producing a series of audible signal impulses sepa-

rated from each other by short intervals of time.

The gear 10 is equipped with bevel gear teeth 10' which drives the bevel pinion 42 on the vertical shaft 43, which is supported at its lower end by the bearing 44, carried by the casing 5. The upper end of this shaft, which is shown broken for simplicity of illustration, carries an exhaust fan 45, which operates in an exhaust hood 46, supported within the casing 5, upon the exhaust conduit or pipe 47.

An additional air pipe 48 discharges into the casing immediately above the flame zone, and extends to a point in the open air, to afford oxygen for combustion.

A check valve 49 is provided in the bellows for preventing the reverse flow of air contained in the extended bellows, so that it will be forced upwardly, and also to prevent back-fire of the ignited gas. Another and similar check valve 48^a is provided at the discharge end of the auxiliary fresh air pipe 48, so that flame will not be communicated to the air in the room outside of the casing.

It is apparent from this description and the drawings that whenever any inflammable gas is forced into the cup-like member 18, ignition will immediately take place, by reason of the constantly active sparking tip which works against the wall of the drum or member 18. This will produce a flame, which will release the shift links 35 and 37, interrupting the automatic action of the blower and igniter, and set in motion the intermittent operation of the audible signal, which will send an alarm throughout the home or building, and continue to operate until the power of the main spring has become exhausted or a person responds, stops the gas leak and sets the combined gas detector and signal for subsequent operation.

The main spring may be of any power capacity, so as to drive the mechanism for one day or as much as a week or more, with a single complete winding; while the speed of rotation, and the number of pins or studs 91 and their spacing (if a plurality) on gear 9, of course, may be such as to give the alarm at any intervals predetermined.

The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

I claim as new:—

1. A gas detector having means for producing intermittently igniting sparks, means for causing a gas charged movement of air in the path of the sparks so produced, and

means released by the generation of a flame by gas flowed in the path of said sparks for producing an audible signal.

2. A gas detector consisting of a closed casing, means for causing air from the outside to flow through the casing, means for producing a series of sparks in the path of the air flowed into the casing, an intermittent signal, and means controlling the signal and adapted to be actuated when a flame is produced in the zone of the sparks.

3. A gas detector consisting of a closed casing, means for causing air from the outside to flow into the casing, means for producing a series of intermittent sparks in the path of air admitted to the casing from said means, and means for interrupting the action of the second named means when a flame is started from gas charged air admitted to the casing by said first means.

4. A combined gas detector and signal consisting of a closed casing, an air moving means for causing air to flow into the casing, means for operating said means, means for producing intermittent sparks in the path of air admitted by said first named means to the casing, a signal, and means for actuating the signal releasable by a flame generated by said sparking means from said gas charged air admitted to the casing.

5. A gas detector comprising a casing, an intermittent spark producing mechanism therein, a blower for causing gas charged air to move into the casing in the path of said spark producing mechanism, and a signal adapted to be set in operation when a flame is generated by said spark producing mechanism from gas charged air admitted to the casing.

6. A gas detector consisting of a casing, an intermittent spark producing mechanism, an intermittent signal producing mechanism, a gear train arranged to alternately operate the two mechanisms, means for maintaining the signal mechanism normally inactive and the spark producing mechanism normally active, and a combustible element for restraining said last means.

7. In a gas detector the combination of a continuously operating clock train, an intermittent alarm operable thereby, an igniter, means operable by said clock train for intermittently operating said igniter, means operable by said clock train for intermittently supplying an air and gas mixture to said igniter, and flame controlled means for disabling said igniter and said supplying means, and being also effective to set in motion said intermittent alarm.

8. In a gas detector the combination of a continuously operating clock train, an igniter operable by said clock train, means operable by said clock train for periodically supplying an air and gas mixture to said igniter, flame controlled means for disabling said igniter

and said supplying means, said means including a spring operated lever and an element destroyable by heat, and means controlled by said disabling means for setting in motion an alarm.

9. In a gas detector the combination of a continuously operating clock train, a rockable lever, an igniter carried by said lever, an abrasive member co-operating with said igniter and adapted to be rotated intermittently by the operation of said rockable lever, a bellows intermittently operated by said clock train and adapted to be disabled, an intermittent signal mechanism, and means including a combustible element for disabling said igniter and said bellows, said disabling means when operated to disable said bellows and said igniter acting to set in motion said intermittent signal mechanism for sounding an alarm.

In testimony whereof I have affixed my signature.

RUDOLPH KRAUS.
